INVENTOR

R. E. Wise

BY Victor J. Evans

ATTORNEY

WITNESSES:—

UNITED STATES PATENT OFFICE.

GUST A. NELSON, OF SEDRO WOOLLEY, WASHINGTON.

VULCANIZER.

Application filed July 9, 1923. Serial No. 650,486.

To all whom it may concern:

Be it known that I, GUST A. NELSON, a citizen of the United States, residing at Sedro Woolley, in the county of Skagit and State of Washington, have invented new and useful Improvements in Vulcanizers, of which the following is a specification.

This invention relates to a vulcanizer, the general object of the invention being to provide an electrically heated steam vulcanizer for use in small shops, garages and the like and which is so formed that the steam pressure can be quickly raised to a vulcanizing pressure.

Another object of the invention is to provide means whereby the operator can apply the pressure to the tube with one hand while he holds the pressure block or adjusts the tube with the other.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a side view of the invention.

Figure 2 is a plan view thereof.

Figure 3 is a longitudinal sectional view.

Figure 4 is an end view.

Figure 5 is a transverse sectional view.

Figure 6 is a plan view showing the heating coils and the insulating means.

In these views 1 indicates the body of the device which is provided with a water chamber 2 and a chamber 3 in which is located the heating coils 4. An inlet pipe 5 is connected with the water chamber and this pipe may be provided with a suitable pressure gage 6. Conductors 7 are connected with the heating coils and with a socket 8 so that the device can be attached to an electric light socket or the like. If desired the pressure gage can be made to shut off the current when the pressure reaches a certain point, any suitable means may be provided for doing this. The bottom 9 of the chamber

3 is held in place by the bolts 10, this bottom holding in position the insulating means 11 for the heating coils. The bolts 10 are extended to form the legs 12 and the bolts at one end of the device have their upper parts extended and provided with the eyes 13 to support a shaft 14 on which the hand lever 15 is pivoted. A notched upright 16 is located at the other end of the device for engaging a latch part 17 formed on the lever for holding the same in adjusted position. The notches are shown at 16' in Figure 4. A slotted tubular member 18 is carried by the lever, the lever passing through the slot therein and a spring 19 is inserted in the tubular member and engages the lever. The lower end of this tubular member is adapted to engage a block 20 which is adapted to be placed on that part of the tube which rests upon the top of the device when the tube is being vulcanized. Thus the tube is held against the hot upper surface of the body by means of spring pressure exerted on the block. This pressure can be regulated by placing the latch part of the handle in various notches in the upright.

From the above it will be seen that the operator can move the handle or lever with one hand while he is adjusting the block and tube with the other. The coils being arranged, as shown, right under the water chamber will quickly produce steam when current is turned thereon so that the device can be used in small shops and garages where a vulcanizer cannot be used continuously.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A vulcanizer of the class described comprising a body having a water chamber in the upper part thereof, a lower chamber, a heating coil in the lower chamber, a removable bottom plate for the lower chamber, bolts for holding the same in place, the lower ends of the bolts being extended to

form legs and the upper portions of the bolts at one end being extended, a shaft supported by the extended portions of these last mentioned bolts, a hand lever pivoted to the shaft, an upright at the other end of the body having notches therein for receiving a part of the hand lever, a member having

a slot therein through which the hand lever passes, a spring in said member engaging the lever, means for introducing water into the chamber and means for connecting the heating coil with a source of supply.

In testimony whereof I affix my signature.

GUST A. NELSON.
